(57) **CLAIM**

The ornamental design for a travel pillow, as shown and described.

DESCRIPTION

FIG. 1 is an isometric view of a travel pillow showing an embodiment of my new design.

FIG. 2 is a top plan view thereof.

FIG. 3 is a front elevational view thereof, which is the same as the rear elevational view.

FIG. 4 is a right side elevational view thereof, which is the same as the left side elevational view.

FIG. 5 is a bottom plan view thereof.

FIG. 6 is an isometric view of a travel pillow showing another embodiment of my new design having a relatively smaller size.

FIG. 7 is a top plan view thereof.

FIG. 8 is a front elevational view thereof, which is the same as the rear elevational view.

FIG. 9 is a right side elevational view thereof, which is the same as the left side elevational view; and,

FIG. 10 is a bottom plan view thereof.

The broken lines in the figures illustrate features that form no part of the claimed design.
